UNITED STATES PATENT OFFICE.

JOSEPH H. STRAUS, JR., OF BALTIMORE, MARYLAND, ASSIGNOR OF ONE-HALF TO
RAYMOND H. WILLIAMS, OF BALTIMORE, MARYLAND.

CLIP USED IN CONCRETE CONSTRUCTION.

1,018,018.

Specification of Letters Patent. Patented Feb. 20, 1912.

Application filed December 5, 1911. Serial No. 663,995.

To all whom it may concern:

Be it known that I, JOSEPH H. STRAUS, Jr., a citizen of the United States, residing at Baltimore city, State of Maryland, have 5 invented certain new and useful Improvements in Clips Used in Concrete Construction, of which the following is a specification.

This invention relates to means for securing 10 reinforcing bars in position in molds for concrete work so as to prevent their displacement (and the consequent injury or ruin of the finished work) while the concrete is being poured or otherwise manipulated previous to setting or hardening.

The general object of the invention is to provide improved means for this purpose especially adapted to the securing together 20 of reinforcing bars which cross each other at right or other angles.

A further object is to provide such securing means of such a character that the concrete worker may make them himself at the work to suit general or particular forms.

25 A further object is to provide securing means with improved means for supporting the secured together bars at a suitable height from the bottom of the mold.

With these and other objects in view, the 30 invention consists in a clip or clamp of the improved form, and of the material herein-after fully described and afterward specifically claimed.

In the accompanying drawings, which 35 illustrate preferred embodiments of the invention, Figure 1 represents a plan view of a pair of reinforcing bars crossing each other and secured together by the improved clamp; Fig. 2 represents a vertical sectional

40 view of a sidewalk or other horizontal concrete construction having reinforcing rods such as shown in Fig. 1 in position therein and positioned and secured by the improved clamp and supports; Fig. 3 represents in

45 perspective the improved combined clamp and support, detached; Fig. 4 represents in perspective view, the clamp and support in position on a pair of reinforcing bars such as shown in Figs. 1 and 2; Fig. 5 represents in perspective view the improved clip 50 or clamp without the supporting leg; and Fig. 6 represents a vertical sectional view through an upright concrete construction, such as a wall or the like, with the clamp

or clip of Fig. 5 therein securing reinforcing bars together.

Like reference characters mark the same parts wherever they appear in the drawings.

Referring specifically to Figs. 1 to 4, inclusive of the drawings A and B indicate 60 reinforcing bars which lie horizontally and cross each other in contact and which are especially intended in this position as reinforcements for horizontal concrete constructions, such as floors, and the like, as at C. 65

My improved clip or clamp and support is indicated as a whole at 1 and is preferably formed of a single piece of flexible stiff wire being bent at one end to form a hook 2 to engage over the lower bar B. From 70 this hook the wire is bent in a direction substantially parallel with the upper bar A to a point 3 where it is bent downward and again, at the point 4, back upon itself forming a leg or support 5. At 6 the wire is 75 again bent horizontally as at 7 and thence upward and back forming a loop to engage over the upper bar A. From this loop the wire is carried along, as at 9, substantially parallel with the bar A, under and past the 80 rod B, and at its opposite end is bent into the form of a hook 10 to engage over the upper bar A.

When in position, as shown in Fig. 2, the 85 two hooks 2 and 10 being engaged over the upper bar A, the stretch 9 passing under the bar B holds it up against the upper bar A, and the legs 5, of which there is one at each crossing of the bars A and B, firmly support the secured together bars A and B 90 in the mold so that the concrete may be poured therein without displacing or disarranging the reinforcements.

In Figs. 5 and 6 the construction is 95 shown without the leg 5, the latter being unnecessary in vertical constructions, as at D, where one of the bars, as A', is vertical and the other as B' crosses in contact with it, and is usually horizontal. In this form the hook 2' engages the bar B' and from 100 this point the wire extends, as at 7', in a substantially vertical direction, until turned horizontally and bent to form the loop 8' to engage around the vertical bar A'. From the loop 8' the wire extends, in sub- 105 substantially horizontal direction, as at 9', crossing the bar B' in contact therewith and binding it against the bar A', and termi-

nating in a horizontal loop 10' engaging around the bar A'.

The construction and operation of the invention will be readily comprehended from the foregoing description, in connection with the accompanying drawing and it will be obvious to those skilled in the art of concrete reinforcement that slight variations may be made in the construction of the parts without departing from the spirit and scope of the invention as hereinafter claimed.

Having thus fully described the invention, what is claimed as new is—

1. A clip for securing together crossing bars comprising a hook at one end engaging around one of the bars, a stretch substantially parallel with said bar crossing outside of and in contact with the second bar to bind it to the first named bar, a loop at the other end of said stretch engaging around the first named bar, a stretch from the loop substantially parallel with the first named stretch to the second bar, and a hook at the end of the last named stretch engaging around the second bar, the last named stretch bent outward substantially at a right

angle and back upon itself, intermediate its ends, to form a supporting leg.

2. The herein-described reinforcement for floors or other horizontal concrete constructions, comprising two horizontal bars crossing and in contact with each other and a combined clamp and support for said bars comprising a wire bent at one end into a loop and embracing the lower bar and carried substantially horizontally a short distance, thence bent downward and doubled back upon itself forming a leg, thence again carried a short distance substantially horizontally and formed into a loop embracing the upper bar, thence carried substantially horizontally in the opposite direction across under in contact with the lower bar and beyond said lower bar, and terminating in a loop embracing the upper bar.

In testimony whereof I affix my signature in presence of two witnesses.

JOSEPH H. STRAUS, JR.
